LIQUID CONGEALING APPARATUS

Malcolm G. Shoemaker, Springfield, Mass., assignor to Westinghouse Electric & Manufacturing Company, East Pittsburgh, Pa., a corporation of Pennsylvania

Application November 24, 1936, Serial No. 112,480

6 Claims. (Cl. 62—108.5)

My invention relates to liquid congealing apparatus, and particularly to an ice tray and grid construction for forming ice blocks suitable for table use.

5 It is an object of my invention to provide improved liquid congealing apparatus from which ice blocks are readily removable without the application of heat.

10 It is another object of my invention to provide an improved stiffening means for flexible grids and furthermore to utilize the stiffening means for pivotally connecting the flexible walls of the grid structure thereto.

15 It is still another object of my invention to provide an improved flexible metal grid structure for forming ice blocks and for thereafter affording ready removal of the ice blocks from the grid structure.

These and other objects are effected by my 20 invention, as will be apparent from the following description and claims taken in connection with the accompanying drawings and forming a part of this application, in which:

Fig. 1 is a top plan view of an ice pan and grid 25 illustrating my invention;

Fig. 2 is a side elevational view of the ice pan and grid shown in Fig. 1 with portions of the ice tray broken away;

Fig. 3 is a view of the grid structure alone 30 shown in its flexed position for the removal of ice blocks therefrom;

Fig. 4 is a perspective view of a leverage device which may be utilized for raising the grid member relative to the ice pan;

Fig. 5 is a transverse sectional view of my improved flexible grid structure;

Fig. 6 is an end view of the grid structure;

Fig. 7 is an end view of the grid structure with the center bar or stiffening strip removed;

40 Fig. 8 is a fragmentary elevational view of the center bar;

Fig. 9 is a detail view of the pivot for one end of the tray; and

Fig. 10 is a plan view of the grid structure as 45 it appears when the central wall member is separated.

Referring to the drawings for a detailed description of my invention, numeral 11 designates a relatively rigid ice pan preferably formed of 50 stamped aluminum. A removable grid member, generally designated by the numeral 12, is disposed in the ice pan 11 in the position shown in Fig. 1 and forms a plurality of cells 13 for forming ice blocks (not shown).

55 The grid member 12 is preferably formed of

two sheets of flexible metal 14 and 15 bent to zig-zag or triangular shape to form the ice cells 13 with outside bends 16 being cut away at 17 to clear the radii of the lower part of the pan 11. The sheets of flexible metal 14 and 15 are preferably formed of stainless steel or other non-corrosive metal and provide vertical dividing walls in the ice pan 11. A central relatively rigid vertical wall member 18 of substantially the same height as the sheets 14 and 15 and also preferably formed of stainless steel or a similar metal, is formed of two sheets of metal 19 and 21, and is interposed between the flexible wall members or sheets 14 and 15. The inner and outer apices of the flexible sheets 14 and 15 freely abut the central wall member 18 and the ice pan 11, respectively.

The sheets of flexible metal 14 and 15 are pivotally joined to the rigid center bar 18 in the following manner. One longitudinal end of each 20 of the sheets 14 and 15 are attached by a pivot pin 21 which freely extends through the members 14, 15, 19, and 20, as clearly shown in Fig. 1. The sheets 14 and 15 are, therefore, pivotally connected to the sheets 19 and 20. A pivoting 25 member 22, shown in detail in Fig. 9, has lugs 24 which are preferably riveted at 23 to the other ends of the sheets 14 and 15 and holds them together, as shown in Figs. 1 and 7. The pivoting member including a horizontal shoulder 25 30 which straddles the center bar 18. As shown in Figs. 3, 6, and 8, the members 19 and 20 of the center bar 18 are held together by a pivot pin 26 located at the opposite end of the grid to the pivot pin 21. A strap 27 for holding an overhanging pin 28 is journaled on the pivot pin 26 for a purpose hereinafter described. The overhanging pin 28 is provided with an offset end 29 (see Fig. 8) which hooks over the horizontal shoulder 25 on the pivoting member 23, when 35 the grid is in its normal position (see Fig. 2 or 3). The sheets 14 and 15 are, therefore, pivotally retained at this end, the shoulder 25 being free to rotate to some extent between the underside of the overhanging pin 28 and the upper side of 40 the center bar 18. In other words, the sheets 14 and 15 are freely retained at one end between the pin 28 and the center bar 18.

A leverage device 30 such as the one shown in 45 Fig. 4 is provided for raising the grid 12 from the ice pan 11 and comprises a handle member 29 pivotally attached to an end of the pan 11 by a pivot 31, to which a vertically extending lifting member 32 is pivotally attached at 33. The han- 50

dle member is also provided with a toe 34 for engaging a support 35 for the ice pan.

In operation, the ice pan 11 is filled with water and the grid 12 is disposed therein in the position shown in Fig. 4. After liquid is frozen in the cells 13, the handle member 29 of the leverage device 30 is rotated, whereupon the toe 34 engages the support 35 and breaks the ice bond between the ice pan 11 and the support. Upward movement of the handle member 29 also raises the vertical lifting member into engagement with the overhanging pin 28 and lifts the grid member 12 relative to the ice pan 11, thus breaking the bond between the ice blocks and the interior surfaces of the ice pan. The grid member 12 is raised along its entire extent and upward flexing is substantially prevented during the raising of the grid relative to the ice pan due to the relatively rigid stiffening member 18, thus insuring that the ice bond between the ice cubes and the ice pan will be broken.

After the ice bond between the ice cubes and the ice pan is broken, the grid with the ice cubes contained therein may be taken hold of and the sheets 14 and 15 flexed, for example, vertically of the stiffening member 18, to the position shown in Fig. 3. The stiffening member 18 obviously remains in its original position. The sheets 14 and 15 pivot about the pivot pin 21 and the pivoting member 22, whereby the grid is flexed a progressively greater amount from the ends to the center thereof, thus freeing the ice cubes from the grid because of the relative movement between the flexible sheets 14 and 15 and the stiffening member 18 and because of the relative movement between portions of the sheets 14 and 15 which define the cells 13.

If it is desired to take the grid 12 apart for cleaning, the strap 27 with the pin 28 may be rotated about the pin 26, the ends of the sheets 14 and 15 being cut out at 37, as shown in Figs. 2 and 3 to permit movement of the strap 27. The sheets 14 and 15 may then be rotated clockwise about the pivot 21 to separate the stiffening member 18 and the sheets 14 and 15.

As shown in Fig. 10, the sheets 19 and 20 of the stiffening member 18 may be provided with outwardly bent portions, shown at 38 in Figs. 1, 5, and 10 for the insertion of a wedge to separate the sheets 18 and 19 to facilitate breaking of the ice blocks from the grid 12. When the sheets 19 and 20 are bent to the position shown in Fig. 10, the sheets 19 and 20 are arched and the ice is broken loose therefrom. If the sheets 19 and 20 are separated a sufficient distance, the flexible members 14 and 15 flex sufficiently to loosen the ice blocks therefrom.

From the foregoing, it will be apparent that I have provided improved liquid congealing apparatus formed of flexible metal from which the frozen liquid may be readily removed without the use of heat. I have furthermore provided a novel stiffening means for facilitating removal of the grid from the ice tray and have provided for rotating the flexible walls of the grid about the pivoted connections to effect easy removal of the ice blocks from the grid.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended claims.

What I claim is:

1. In a freezing tray, in combination, a container pan, an elongated grid structure for said pan for dividing its frozen contents into a plurality of ice blocks, said grid comprising, a longitudinally extending central wall which is relatively rigid against vertical bending, and two longitudinally extending relatively flexible metal block-forming members lying upon opposite sides of said central wall and each having pivot connections at its two longitudinal ends to said central wall, each of said flexible members being bodily distortable in a vertical direction by pivoting about its two end pivot connections, and force-multiplying means for forcing said central wall upwardly from said pan. 5

2. In a freezing tray, in combination, a container pan, an elongated grid structure for said pan for dividing its frozen contents into a plurality of ice blocks, said grid comprising, a longitudinally extending central wall which is relatively rigid against vertical bending, and two elongated flexible metal strips lying upon opposite sides respectively of said central wall and deformed laterally so as to form a series of ice block 25 compartments, each of said flexible strips having pivot connections to said central wall at its two longitudinal ends and being readily movable relative to said central wall at all points intermediate said pivot connections, and force-multiplying 30 means for forcing one end of said central wall upwardly from said pan. 20

3. In a freezing tray, in combination, a container pan, an elongated grid structure for said pan for dividing its frozen contents into a plurality of ice blocks, said grid comprising, a longitudinally extending central wall which is relatively rigid against vertical bending, and two elongated flexible metal strips lying upon opposite sides respectively of said central wall and 40 bent into a zig-zag shape in plan view to form a series of ice block compartments, each of said flexible strips being pivotally connected at its two opposed ends to said central wall and being otherwise detached therefrom whereby to permit ready distortion of said flexible strips relative to said central wall, and force-multiplying means 45 for forcing said central wall upwardly from said pan. 5

4. In a freezing tray, in combination, a container pan, an elongated grid structure for said pan for dividing its frozen contents into a plurality of ice blocks, said grid comprising, a longitudinally extending central vertical wall formed of two laterally flexible metal plates lying substantially in face to face contact and connected together only at their two opposed end portions whereby said plates may be spread laterally apart by distortion, and two longitudinally extending flexible metal dividing members lying upon opposite sides of said central wall and each connected thereto at the two longitudinal ends thereof, each of said flexible metal dividing members being readily laterally distortable so that they may be spread laterally outwardly intermediate their connected end portions, and means in the central wall structure for cooperating with a tool for laterally spreading apart the two plates of said central wall to facilitate the removal of the frozen ice blocks after the grid and ice contents have been removed from the pan. 60

5. In a freezing tray, in combination, a container pan, an elongated grid structure for said pan for dividing its frozen contents into a plurality of ice blocks, said grid comprising, two lat- 75

erally flexible metal plates lying substantially in face to face contact and connected together at their end portions and forming a central vertical dividing wall, two flexible metal dividing members capable of elongation by distortion and lying upon opposite sides of said central vertical wall and each connected thereto at its two longitudinal end portions, and means in the central wall structure for cooperating with a tool for laterally spreading apart the two flexible plates of said central wall after the grid and ice contents have been removed from the pan and thereby causing a lateral spreading apart of said two flexible metal dividing members, whereby to facilitate the removal of the frozen ice blocks.

6. In a freezing tray, in combination, a con-

tainer pan, an elongated grid structure for said pan for dividing its frozen contents into a plurality of ice blocks, said grid comprising, two stretchable longitudinally extending flexible metal dividing members connected together only at their longitudinal end portions and being free to spread laterally apart at their intermediate portions by a stretching distortion thereof, and means in the grid structure for cooperating with a tool for simultaneously spreading and stretching said two dividing members after the grid and ice contents have been removed from the pan, whereby to facilitate the removal of the frozen ice blocks.
